UNITED STATES PATENT OFFICE.

DAVID L. LINDQUIST, OF HARTSDALE, NEW YORK, ASSIGNOR TO OTIS ELEVATOR COMPANY, OF JERSEY CITY, NEW JERSEY, A CORPORATION OF NEW JERSEY.

SAFETY DEVICE FOR ELEVATORS.

Application filed August 27, 1923. Serial No. 659,442.

My invention relates to elevators or similar apparatus in which a car or load carrying means is operated within certain definite limits of travel and which in the stopping operation is adapted to be retarded by an electric dynamic brake.

It is customary to provide automatic slow down and stop at the terminal landings of elevators, or similar load carrying apparatus operated within certain definite limits of travel and an electric dynamic brake is used to automatically retard the elevator. Serious trouble would result if the dynamic braking action should fail to retard the elevator in the stopping operation at the terminal stopping points. With high speed elevators in particular, it is practically impossible to provide sufficient distance of overrun beyond the floor landings at the top and bottom of the hatchway or well room, so as to prevent the car striking the overhead work or the bottom of the pit of the hatchway should the dynamic braking action upon the motor fail to retard the car sufficiently in the stopping operation, thereby permitting the car to continue to run at practically full speed until the final up or down limit stop switch is opened to cut off the power to the motor.

The present invention has for its object to provide means to effect the immediate interruption of the power to the motor and apply the elevator mechanical brake to stop the car in case the dynamic brake does not sufficiently retard the car during the normal automatic slow down as it approaches its terminal stopping points.

I attain this object by the mechanism illustrated in the accompanying drawings, in which—

Figure 1 shows the application of my invention to an elevator driven by a two speed alternating current motor in the control of which the means to effect the immediate interruption of the power to the motor as mentioned above is dependent upon the amount of current in the slow speed windings of the motor.

Figure 2 shows the application of my invention to an elevator driven by a two speed alternating current motor in the control of which the means to effect the immediate interruption of the power to the motor as mentioned above is dependent upon the speed of the elevator and upon the operation of the

electromagnet switch controlling the fast and slow speeds of the motor.

Figure 3 shows the application of my invention to an elevator driven by a direct current motor in the control of which the means to effect the immediate interruption of the power to the motor as mentioned above is dependent upon the current in the armature of the motor, the voltage across the armature, or the current in the motor field; or upon the combined effect of any two or all three of these.

Referring to all the figures in detail, an elevator car C is shown in a hatchway A suspended from one end of a hoisting rope or cable 1 that is led from the car over an overhead work B and from there down to a driving sheave 2 on a shaft 3 of an electric motor D that is adapted to operate the car. There is the usual electro-mechanically operated brake H for stopping the car; also the top and bottom landings E and F. For controlling the car C to stop it at the terminal landings, there are switches 4, 5 and 6 near the top floor landing E adapted to be operated by the movement of the car in the order named to stop the car at the top floor landing and switches 7, 8 and 9, similar to switches 4, 5 and 6, near the bottom floor landing F adapted to be operated by the movement of the car in the order named to stop the car at the bottom floor landing. To the side of the car C there is affixed a cam 10 for operating the switches 4, 5, 6, 7, 8 and 9 and in the car there is a controlling switch G for operating the car. There are also the usual electro-magnetically operable up and down reversing switches I and J for controlling the motor D, and consequently the movement of the car, the switch I controlling the motor for the ascending direction of car travel and the switch J for the descending direction of travel.

In Figure 1 in addition to the above parts there is an electro-magnetically operable fast speed switch K to control the speed of the motor M, which in this case is shown as a three phase two speed alternating current motor. There is also an electro-magnetically operable switch L having two series coils or windings 11 and 11', and two making contacts 12 and 12'.

The operation of the apparatus as shown in Figure 1 is as follows. Assume that the eleva-

tor car C is at its bottom terminal landing F and that it is desired to operate it to cause it to travel to its top terminal floor landing E. The lever 13 of the car switch G 5 will be moved to the right and its contact segment 14 brought into contact with contact 15 of the switch, whereupon an electrical circuit will be established as follows: from line I, by wire 16, contact 17 of the 10 up reversing switch I, by wire 18, common wire 19 of contacts 20 and 21 of the switch G, contact 20, segment 14 and contact 15, by wire 22, through a winding 23 of the up reversing switch I, by wire 24, through contacts 25 of the 15 up limit stop switch 5, by wire 26, junction point 27, by wire 28, through contacts 29 of the up limit stop switch 6, by wire 30, junction point 31, by wire 32, junction point 33, by wire 34, contact 35 of the fast speed switch 20 K, by wire 36 to the line II. The winding 23 of the up reversing switch I has been energized as a result of the closing of the circuit just traced and operates the reversing switch I to close its contacts, and they in closing, close 25 supply circuits to the hoisting motor D for it to operate and hoist the car. The brake H will be released at the same time. Circuits to the motor are as follows: from line I, by wire 16, contact 17 and contact 37 of the up reversing switch I, now closed, by wire 38, junction point 39, by wire 40, through the winding 11 of the electro-magnetically operable switch L, by wire 41, through a slow speed winding 42 of the motor, by wire 43, contact 44 of the 30 fast speed switch K, by wire 45, through contacts 46 of the fast speed switch K, by wire 47, through another slow speed winding 48 of the motor, by wire 49, junction point 33, by wire 34, contact 35 of the fast speed switch 35 K, and by wire 36 to the line II. Another circuit closed to the motor D at this time is as follows: from line III, by wire 50, contacts 51 and 52, now closed, of the up reversing switch I, by wires 53 and 54, junction point 55, by wire 56, through the winding 11' of the electro-magnetically operable switch L, by wire 57, through another slow speed winding 58 of the motor, by wire 59, through contacts 60 of the fast speed switch K, by wire 61, contacts 46 40 of the switch and by wire 47 to the line II by way of the slow speed winding 48 as traced before. The hoisting motor will start as a result of the closing of the reversing switch I and the circuits just traced to its slow speed 45 windings, and hoist the car. Moving the operating switch lever 13 further to the right will bring its contact segment 14 in contact with another contact 62 of the switch, closing a circuit as follows: from line I to contact 20 of the switch G as previously traced, segment 14 and contact 62, by wire 63, through contacts 64 of the up limit switch 4, by wire 65, contact 66 of the down limit switch 7, by wire 67, through the winding 68 of the fast 50 speed switch K, by wire 69, contact 35 of the fast speed switch K, and wire 36 to the line II. The winding 68 of the fast speed switch K has been energized by the circuit just traced and operates its switch to close its top contacts and open its bottom contacts, the switch in operating opening its bottom contacts before closing its top contacts. With the top contacts of the switch K closed, and the bottom contacts open, the motor is operating on the fast speed windings, the slow speed windings of the 55 motor having been short-circuited. The circuits to the fast speed windings of the motor D are as follows: from line I, by wire 16, contacts 17 and 37 of the up reversing switch I, by wire 38, junction point 39, by wire 70, contact 71 of the fast speed switch K now closed with contact 44 of this switch, by wire 43, through fast speed windings 72 and 73 of the motor, by wire 47, by wire 74, contacts 75 and 35 of the fast speed switch K and by wire 36 to the line II. Another circuit to the motor fast speed windings is as follows: from line III, by wire 50, contacts 51 and 52 of the up reversing switch I, by wires 53 and 54, junction point 55, by wire 76, through contacts 77 and 78 now closed of the fast speed switch K, by wire 79, a contact 60 of the switch, by wire 59, through fast speed windings 80 and 73 of the motor, and by wire 47 to the line II as traced before. The hoisting motor D is now 60 operating on its fast speed windings and hoisting the car at fast speed.

The car operating at full speed in its approach to the top terminal floor landing will, as a first step in the normal operation of automatically stopping at the top terminal floor landing, strike by the cam 10 thereon the arm of the slow down limit switch 4 and effect the opening of the contacts 64 of this switch. Switch 4 is positioned at a distance from the terminal landing such that the speed of the elevator will be sufficiently reduced to permit the elevator to be stopped at the landing. The contacts 64 upon opening open the circuit to the winding 68 of the fast speed switch K, causing the winding to become deenergized and the switch K to open its top contacts, which were closed when the winding was energized, and close its bottom contacts. 65 This results in the motor D operating on its slow speed windings 42, 48 and 58. It is obvious that the retarding torque or the electric dynamic braking action of the slow speed windings of the hoisting motor D will be large until the motor speed is reduced to 70 that of its slow speed windings. As the car continues toward the terminal landing, cam 10 engages with auxiliary stop switch 5 and opens its contact. If sufficient current is obtained in the slow speed windings of the 75 motor, the windings 11 and 11' of the switch L in circuit with the slow speed windings of the hoisting motor will become energized and close the contacts 12 and 12' of the switch. The contacts 12 of the switch L, being con-

neeted in parallel by the wires 82 and 83 with the contacts 25 of the limit stop switch 5, serve to hold closed the circuit to the winding 23 of the reversing switch I, which otherwise 5 would have been deenergized by the opening of the contacts 25 of the limit stop switch 5. Thus it is seen that the opening of the limit stop switch 5 has no effect, provided there is sufficient current in the slow speed winding 10 of the motor at the time this switch opens to keep the windings of switch L sufficiently energized so that contacts 12 remain closed. When the cam 10 strikes the limit stop switch 6, causing it to open its contacts 29, and effect 15 the de-energization of the winding 23 of the reversing switch I, thereby effecting the opening of the contacts of the reversing switch and the application of the mechanical brake H, the speed of the hoisting motor and 20 consequently the speed of the car will have been sufficiently reduced by the electric dynamic brake action of the motor so that the application of the mechanical brake H, when the car is at a point in its travel correspond- 25 ing to the opening of limit switch 6, will stop the car at the top terminal floor landing without any possibility of the car coasting into the overhead work. If, however, the dynamic brake action of the motor were re- 30 duced or entirely absent and if the mechanical brake be applied when the car is at a point in its travel corresponding to the opening 35 of limit switch 6, the car would coast a much greater distance than when the dynamic brake action is present and would not only not stop at the top terminal landing, but in all probability would coast far enough 40 to strike the overhead work. To overcome this difficulty, the mechanical brake is applied sooner when the dynamic brake action is not sufficient to properly retard the car. This is accomplished by means of the limit 45 stop switch 5 with contacts 25 in connection with contacts 12 on switch L. The lack of sufficient current to energize the windings 11 and 11' of the switch L or in other words the lack of sufficient dynamic brake action, for the reason that one phase of the slow speed 50 windings of the hoisting motor is open, or for any other reason, would result in the contacts 12 remaining open and therefore in the de-energization of the reversing switch winding 23 when the limit stop switch 5 opens, as contacts 12 would no longer shunt 55 contacts 25 of this limit switch. The auxiliary limit switch 5 is arranged to be opened immediately after the opening of limit switch 4 or as soon thereafter as will permit of switch L closing its contacts in normal 60 operation. The opening of the reversing switch at this time permits the mechanical brake H to be applied when the car is at a point in its travel corresponding to the opening of the limit switch 5, and the car is 65 brought to rest entirely by mechanical brake action. The distance available in which the car may slide before striking the overhead work is, however, much greater in this case than when the brake is applied when the car is at a point corresponding to the opening of 70 limit switch 6 and therefore there is little chance of the car coasting far enough to strike the overhead work.

In Figure 2, in addition to the parts given above as common to all the figures, there is an 75 electro-magnetically operable fast speed switch K to control the speed of motor M, which in this case is shown as a three phase two speed alternating current motor as in Figure 1. There is also an electro-magneti- 80 cally operable switch M having a coil 84 and breaking contact 85, adapted in case of the failure of the electric dynamic brake retardation or slow down of the car C in stopping at its terminal landings, including a failure of 85 the fast speed switch to open its top contacts at the proper time as well as the failure of the dynamic brake itself, to operate to stop the car before it can continue to move beyond these landings sufficiently to reach and hit 90 the overhead work placed above its up limit of travel or the bottom of the pit below its down limit of travel. The failure of the dynamic brake is determined in this case from the speed of the elevator car by means 95 of a contact 86 operated by a centrifugal governor N driven by the movement of the car in the usual way. The contact 86 is adapted to be closed when the elevator is running at fast speed and to open when the 100 speed becomes a certain predetermined amount lower than fast speed.

The operation of the apparatus as shown in Figure 2 is as follows. Assume that the elevator car C is at its bottom terminal landing F and that it is desired to operate it to cause it to travel to its top terminal floor landing E. The lever 13 of the car switch G will be moved to the right and its contact segment 14 brought into contact with contact 15 of the switch completing the circuit for the up reversing switch coil as follows: from line I, by wire 16, contact 17 of the up reversing switch I, by wire 18, common wire 19 of contacts 20 and 21 of the switch 110 G, contact 20, segment 14 and contact 15, by wire 22, through a winding 23 of the up reversing switch I, by wire 87, through contacts 29 of the up limit stop switch 6, by wire 88, through contacts 25 of the up limit stop 115 switch 5, by wire 89, junction point 90, by wire 32, junction point 33, by wire 34, contact 35, by wire 36, to line II. The winding 23 of the up reversing switch I will be energized as a result of the closing of the circuit just traced and operates the reversing switch I to close its contacts, and in closing, they 120 close supply circuits to the hoisting motor D. The brake H will be released at the same 125 time. The main circuits to the motor are 130

the same as traced in connection with Figure 1 except that windings 11 and 11' of switch L are not in Figure 2. As the change in circuit occasioned by this omission is obvious, it is not thought necessary to trace these circuits again. The hoisting motor will start as a result of the closing of the reversing switch I and will run on its slow speed windings and hoist the car. Moving the operating switch lever 13 further to the right will bring its contact segment 14 in contact with contact 62 of the switch, closing a circuit for the coil of the fast speed switch K in the same way as traced under Figure 1. It is not thought necessary to trace this circuit again. The switch K will then operate as described under Figure 1, closing the circuits to the fast speed windings of the motor. The hoisting motor D is now operating on its fast speed windings and hoisting the car at fast speed.

When the switch K closes its top contacts, a circuit is closed for the coil 84 of switch M as follows: from line I, by wire 16, contacts 25 17 and 37 now closed, by wire 38, junction point 39, by wire 91, contacts 92 and 93 on top of switch K now closed, by wire 94, coil 84 of switch M, by wire 95, junction point 96, by wire 49, junction point 33, by wire 34, contact 35, by wire 36, to line II. Contacts 92 and 93 are shunted by contact 86 on the governor N by wires 97 and 98. Thus it is seen that the winding of switch M will be energized when the reversing switch and fast speed switches are closed and also when the reversing switch and contact 86 on governor are closed independent of the condition of the fast speed switch. A contact 85 on switch M is connected between the outside of contacts 25 of limit switch 5 and the outside of contacts 99 of limit switch 8 by wires 100 and 101 and is adapted to be open when the coil 84 of switch M is energized. The contact 86 on the governor is adapted to be closed as stated above when the motor is running at fast speed.

The car operating at full speed in its approach to the top terminal floor landing will, as a first step in the operation of stopping at the top terminal floor landing, open contacts 64 of limit switch 4, thereby deenergizing coil 68 of switch K, which in turn opens its top contacts, and closes its bottom contacts, causing the motor to operate in slow speed as described under Figure 1. If the proper dynamic slow down is obtained, the contact 86 on governor will open as soon as the dynamic brake begins to slow down the motor, thereby breaking the circuit to coil 84 of switch M, the shunt circuit to this coil through contacts 92 and 93 on switch K already being opened. The switch M will then close its contact 85. As the car moves upward, the cam 10 will strike the roller on limit switch 5 and open contacts 25 shortly after

switch 4 was operated. With normal conditions, that is with the proper dynamic braking action present, the opening of contacts 25 will have no effect as a circuit to the reversing switch coil 23 will still be complete 70 as follows: from line I to coil 23 as previously traced, by wire 87, contacts 29 of limit switch 6, by wire 100, contact 85 of switch M, by wire 101, contacts 99 of limit switch 8, now closed, junction point 90 and 75 to line II as previously traced. When the cam 10 on the car strikes limit switch 6, contacts 29 on this switch will be opened, breaking the circuit of the reversing switch coil 23, thereby causing the reversing switch to 80 open and cut off current from the motor and apply the brake II and stop the car at the top terminal floor landing.

It is seen that in the operation just outlined, the dynamic brake action of the motor 85 will have reduced the speed of the car sufficiently before the application of the mechanical brake II to insure that the car will stop at the top terminal floor landing and will not slide beyond this landing enough to 90 strike the overhead work.

Should the dynamic brake action not be present however after the opening of contacts 64 of limit switch 4, the contact 86 on governor switch will remain closed, thereby 95 keeping winding 84 of switch M energized and the contact 85 of this switch open. Under the e conditions, the car will proceed at practically full speed, and the opening of contacts 25 of limit switch 5 will break the 100 circuit for the reversing switch coil 23, thereby causing this switch to open its contacts and cut off current from the motor and apply the mechanical brake II when the car is at a point in its travel corresponding to the 105 point of opening of limit switch 5. The extra distance through which the car may slide before striking the overhead work permits the car to be brought to rest by the mechanical brake alone with little chance of the car 110 coming far enough to strike the overhead work.

There is another element which may enter into the failure of the dynamic brake and that is a failure of the fast speed switch K 115 to open its top contacts when the limit switch 4 is opened. This may result from the sticking of the cores of the switch from residual magnetism or from other causes. Should this happen when limit switch 4 is 120 opened by the cam 10 on the car, the circuit for the coil 84 of switch M would remain closed through contacts 92 and 93 on switch K and the contact 85 would remain open. Then the opening of limit switch 5 would 125 open the reversing switch and stop the car as outlined above.

In Figure 3, in addition to the parts given above as common to all the figures, there are electro-magnetically operable switches Q, P, 130

- Q, R and S, and resistance T, the motor D shown in this figure being a direct current motor with separately excited field SF. Switch S is the accelerating switch to control 5 the resistance T in series with the armature of the motor. Switch R may be called a fast speed switch in that it controls the accelerating switch S and is itself subject to the operating switch in the car. Switches 10 O, P and Q are adapted in case of the failure of the electric dynamic brake retardation or slow down of the car C in stopping at its terminal landings to operate to stop the car before it can continue to move beyond these 15 landings sufficiently to reach and hit the overhead work placed above its up limit of travel or the bottom of the pit below its down limit of travel. The failure of the dynamic brake is determined in this case from the current in 20 the motor armature, the voltage across the armature, and the current in the field. The contact on switch O is adapted to be closed if the voltage across the armature falls below a predetermined value: the contact on switch 25 P is adapted to be closed if the current in the armature is above a predetermined value; and the contact on switch Q is adapted to be closed if the current in the field is above a predetermined value. 30 The operation of the apparatus shown in Figure 3 is as follows: Assume that the car C is to be run from the bottom to the top terminal landings. The lever 13 of the car switch G will be moved to the right and its 35 contact segment 14 brought into contact with contact 15 of the switch, establishing an electrical circuit as follows: from the minus supply line, by wire 102, junction point 103, by wire 104, junction point 105, by wire 106, contact 40 21, by wire 19, contact 20, segment 14, contact 15, by wire 22, coil winding 23 of reversing switch I, by wire 87, contacts 29 of limit switch 6, by wire 88, contacts 25 of limit switch 5, by wire 89, junction point 90, by wire 107, junction point 108, by wire 50 to the plus supply line. The winding 23 of the reversing switch I has been energized by the closing of the circuit just traced and operates the reversing switch I to close its 45 contacts thereby closing circuits to the hoisting motor D as follows: from the plus supply line, by wire 50, contacts 51 and 52 of switch I, by wire 109, junction point 110, by wire 111, junction point 150, by wire 113, through armature 114 of motor D, by wire 115, junction point 151, by wire 118, contacts 37 and 17 of switch I, by wires 119 and 120, junction point 121, resistance T, junction point 103, by wire 102, to the minus supply 50 line. The closing of the reversing switch I completes the circuit for the brake magnet H, which operates and releases the mechanical brake. The circuit for the motor field is completed at the same time as follows: 60 from the plus supply line, by wire 50, by wire 122, contacts 123 and 124 on switch I now closed, by wire 125, junction point 126, by wire 127, field SF of motor D, by wire 128, winding 129 of switch Q, by wire 130, junction point 131, by wire 132, junction point 70 105, by wire 104, junction point 103, by wire 102 to the minus supply line. The hoisting motor will start as a result of the closing of the reversing switch, the motor field and brake magnet being energized, and hoist the 75 car. Moving the operating switch lever 13 further to the right will bring its contact segment 14 in contact with another contact 62 in the switch, closing a circuit for the coil of switch R as follows: from the minus line 80 to contact 20 of switch G as previously traced, segment 14, contact 62, by wire 63, contacts 64 of limit switch 4, by wire 65, junction point 66, by wire 67, coil 133 of switch R, by wires 69, 122 and 50 to the plus supply line. 85 The coil of switch R has been energized and this switch closes its contact 134, completing a circuit for the coil of the accelerating switch S as follows: armature 114 of motor D, by wire 115, junction point 116, by wire 90 135, contact 134, by wire 136, coil 137 of switch S, by wire 138, junction point 110, by wire 111, junction point 150, by wire 113 to armature 114. Thus it is seen that the accelerating switch coil S is connected across 95 the armature of the motor. The coil of switch S being energized will cause the resistance to be cut out in steps in the well known way. 100 The coil 139 of switch O is also connected across the armature of the motor between junction points 116 and 112, the remainder of the circuit being the same as traced above for the coil 137 of switch S. The coil 139 is adapted to operate switch O to open its 105 contact 140 when the voltage across the armature has attained a predetermined value, which value is in this case just slightly below line voltage. Therefore when the motor is running at full speed, the contact of switch 110 O will be open. 110 The coil 117 of switch P is connected in series with the armature of the motor and is adapted to operate and close the contact 141 of this switch when the current in the armature of the motor has attained a predetermined amount, this amount being such that the motor will have sufficient dynamic braking action with this amount of current in the armature, during the slowing down period. 115 120 The coil 129 of switch Q is connected in series with the field winding of the motor as outlined above, and is adapted to operate and close the contact 142 of this switch when the current in the field circuit of the motor is sufficient to insure that the motor will have the proper dynamic braking action during the slowing down period. 125 130 With the car operating at full speed in the up direction, its approach to the top terminal

floor landing will, as a first step in the operation of stopping at the top terminal floor landing, effect the opening of contacts 64 of limit switch 4, thereby opening the circuit to the coil of switch R. Switch R will then open its contact 134 breaking the circuit to the coil 137 of switch S. Switch S will open its contacts and insert resistance T in series with the armature 114 of the motor. Switch R also closes its contact 152 completing the dynamic brake circuit for the motor. This circuit includes coil 117 of switch P as above stated and may be traced from the motor armature 114, by wire 115, coil 117 of switch P, by wire 153, contact 152 by wire 154 through dynamic brake resistance 155, junction point 150, by wire 113 to armature 114. If the proper dynamic slow down is obtained, the voltage across the armature of the motor will be reduced sufficiently to cause coil 139 on switch O to be de-energized enough so that contact 140 on this switch will close; the current in the dynamic brake circuit will remain high enough to keep coil 117 of switch P energized and contact 141 of this switch closed; also, the current in the field will remain high enough to keep coil 129 of switch Q energized and contact 142 of this switch closed. As the car moves upward, the cam 10 will strike the roller on limit switch 5 and open contacts 25 shortly after switch 4 was operated. With normal conditions, that is with the proper dynamic braking action present, the opening of contacts 25 will have no further effect, as a circuit to the reversing switch coil 23, will still be complete as follows: from the minus supply line through contacts 29 of limit switch 6 as previously traced, by wire 100, contact 142 of switch Q now closed, by wire 143, contact 141 of switch P now closed, by wire 144, contact 140 of switch O now closed, by wire 101, contact 99 of limit switch 8, this contact having closed when car moved away from lower terminal landing, by wire 145, junction point 90, by wire 107, junction point 108, by wire 50 to the plus supply line. When the cam 10 on car strikes limit switch 6, contacts 29 on this switch will be opened, breaking the circuit of the reversing switch coil 23 just traced, thereby causing the reversing switch to open and cut off current from the motor and apply the brake H and stop the car at the top terminal floor landing.

In this case as in connection with Figures 1 and 2, it is seen that in the operation just outlined, the dynamic brake action of the motor will have reduced the speed of the car sufficiently before the application of the mechanical brake H to insure that the car will stop at the top terminal floor landing and will not slide beyond this landing enough to strike the overhead work.

Should the dynamic brake action obtained

after the opening of contacts 64 of limit switch 4 not be sufficient, the contacts of one or more of switches O, P and Q will remain open; that is, if the armature voltage is not reduced, coil 139 of switch O will remain energized and keep the contact 140 of this switch open; if the current in the dynamic brake circuit is reduced below the value required to give the proper dynamic braking action, the coil 117 of switch P will be sufficiently de-energized to cause this switch to open its contact 141; and if the current in the field SF is not sufficient to give the proper dynamic brake action, the coil 129 of switch Q will be sufficiently de-energized to cause this switch to open its contact 142. If any one or more of these conditions exist, the car will proceed at practically full speed, and the opening of contacts 25 of limit switch 5 will break the circuit for the reversing switch coil 23, thereby causing this switch to open its contacts and cut off current from the motor and apply the mechanical brake H when the car is at a point in its travel corresponding to the point of opening of limit switch 5. The extra distance through which the car may slide before striking the overhead permits the car to be brought to rest by the mechanical brake alone with little chance of the car coasting far enough to strike the overhead work.

When the cam 10 on the car leaves the limit stop switches 7, 8 and 9, they are closed, each being returned to its closed position, as by a spring 81. The closing of switches 7, 8 and 9 conditions circuits to be closed by movement to the left of the operating switch lever 13 of the operating switch G for a down direction of car travel. Since the circuits through the limit stop switches 7, 8 and 9 are closed similarly to the circuits closed through the up limit stop switches 4, 5 and 6 described herein, it is not thought necessary to trace them or describe the down operation of the car with my invention applied thereto.

What I claim as new and desire to secure by Letters Patent of the United States is:

1. A control system for an elevator car comprising, a motor for raising and lowering the car, a source of power for said motor, a dynamic brake circuit for said motor, switching mechanism for disconnecting said motor from said source, a switch automatically operated upon the car reaching a predetermined point in the hatchway to complete said dynamic brake circuit, a second switch automatically operated upon the car passing a predetermined distance beyond said point to cause the disconnection of said motor from said source, and a third switch automatically operated upon the car passing beyond said point, but prior to the operation of said second switch, to cause the disconnection of said motor from said source in

the event of insufficient dynamic braking action, with the dynamic brake circuit completed.

2. A control system for an elevator car comprising, a motor for raising and lowering the car, a source of power for said motor, slow-down mechanism for said motor, switching mechanism for disconnecting said motor from said source, a switch automatically operated upon the car reaching a predetermined point in the hatchway to cause the operation of said slow-down mechanism to slow down the motor, a second switch automatically operated upon the car passing a certain distance beyond said point to cause the operation of said switching mechanism to disconnect said motor from said source, and a third switch automatically operated after the car has passed said point but before it has passed said certain distance beyond said point to cause the operation of said switching mechanism to disconnect the motor from said source in the event that the action of the slow-down mechanism, when operated, is insufficient to cause the desired slowing down of the motor.

3. A control system for an elevator car comprising, a motor for raising and lowering the car, a source of power for the motor, a dynamic brake circuit for the motor, a switch operable as the car approaches a predetermined point to complete said circuit, a second switch operable as the car approaches still closer to said point to cause the disconnection of the motor from said source, and a third switch dependent on the current in the dynamic brake circuit for rendering the operation of the second switch ineffective.

4. A control system for an elevator car comprising, a motor for raising and lowering the car, a source of power for the motor, a dynamic brake circuit for the motor, a switch operable as the car approaches a predeter-

mined point to complete said circuit, a second switch operable as the car approaches still closer to said point to cause the disconnection of the motor from said source, and a third switch, having an operating winding in the dynamic brake circuit, for by-passing the second named switch.

5. In combination, an alternating current multiphase motor, a source of power for said motor, means for dynamically braking said motor, means for later causing the disconnection of said motor from said source, a switch having windings controlled by the motor current during the operation of the dynamic braking means for rendering the second named means ineffective.

6. In combination, an alternating current motor having slow and fast speed windings, a source of power for said motor, means operable while the motor is running for connecting the slow speed windings of said motor to the source so as to dynamically brake the motor, means for disconnecting the motor from said source, and means dependent on the current in the slow speed windings of the motor during the dynamic braking operation for controlling the operation of the disconnecting means.

7. In combination, an alternating current motor having slow and fast speed windings, a source of power for said motor, means operable while the motor is running for connecting the slow speed windings of said motor to the source so as to dynamically brake the motor, means for disconnecting the motor from said source, and a switch having windings in circuit with the slow speed windings of the motor for controlling the operation of said disconnecting means.

In testimony whereof, I have signed my name to this specification.

DAVID L. LINDQUIST.
